UNITED STATES PATENT OFFICE.

FRANK B. JOHNSTON, OF NEW YORK, N. Y., ASSIGNOR TO AMERICAN SAFETY DEVICE COMPANY, OF NEW YORK, N. Y., A CORPORATION OF NEW YORK.

SCAFFOLDING.

Application filed February 28, 1924. Serial No. 695,662.

To all whom it may concern:

Be it known that I, FRANK B. JOHNSTON, a citizen of the United States, and a resident of the city, county, and State of New York, 5 have invented certain new and useful Improvements in Scaffolding, of which the following is a specification.

This invention relates to scaffolding and has for its primary object to provide certain 10 improvements in scaffolding such as is used by masons or workmen in the erection of a building in which there is provided an unobstructed workmen's platform and means for supporting the mortar, brick or other 15 materials so that the same will be easily accessible and not necessitate frequent stooping by the workmen.

More particularly, I propose in one embodiment of my present improvements to 20 provide a main material receiving platform suitably supported by hoisting devices, and a subjacent workmen's platform suspended from the material receiving platform and extending laterally beyond one side thereof.

25 It is one of the important objects of my present disclosure to provide adjustable means for suspending the workmen's platform from the material receiving platform whereby the former may be readily adjusted 30 and positioned so that it will not encounter cornices or other projections from the wall being erected as the scaffolding is raised or lowered. This suspending means for the workmen's platform has another important 35 advantage, in that should one of the hoisting cables break, the weight of the materials on the main platform will cause the workmen's platform to be automatically swung inwardly and tightly bear against the face of 40 the building wall so that through the medium of the suspending means, the main platform with the materials thereon will be sustained against complete collapse. The improved scaffolding also enables the main 45 platform to be loaded with the materials without interference with the workmen upon the subjacent platform.

It is a further general object of the invention to provide scaffolding of the above 50 character the several parts of which may be easily and quickly connected in operative relation, and which is strong and substantial while relatively light in weight.

With the above and other objects in view, 55 the invention consists in the improved scaf-

folding and in the form, construction and relative arrangement of the several parts as will be hereinafter more fully described, illustrated in the accompanying drawing, and subsequently incorporated in the sub- 60 joined claims.

In the drawing wherein I have shown one simple and satisfactory embodiment of the invention and in which similar reference characters designate corresponding parts. 65 throughout the several views—

Figure 1 is a transverse sectional view through the improved scaffolding showing the workmen's platform in normal position with respect to the building wall in full 70 lines and in dotted lines in an adjusted position whereby said platform may pass a projecting cornice in the vertical adjustment of the scaffolding;

Figure 2 is a fragmentary side elevation 75 of the scaffolding;

Figure 3 is a detail sectional view taken on the line 3—3 of Figure 1;

Figure 4 is a similar section taken on the line 4—4 of Figure 1; and, 80

Figure 5 is a view similar to Figure 1 illustrating another adjustment of the workmen's platform, whereby the latter may be positioned closely adjacent the face of the wall between vertical piers or columns. 85

As herein shown, the main platform which supports the mortar, bricks and other masonry materials, consists of a plurality of boards 5 which are laid in parallel relation in a common plane and supported upon spaced putlogs each of which consists of a pair of angle bars or beams 6 disposed in spaced parallel relation to each other. At their opposite ends these angle bars have their vertical flanges connected by the spaced bolts 7 which are engaged upon the base portion of the angular stirrup or frame 8 of a hoisting device, said base portion of the frame being positioned between the angle bars 6. The outer boards 5 of the 90 platform also extend between the parallel upwardly projecting side portions of the frame 8. Thus it will be understood that the boards of the platform and the angle bars 6 constituting the spaced putlogs are 95 substantially locked together so that their independent relative movement transversely of the scaffolding is prevented.

The hoisting devices above referred to constitute no essential feature of my pres- 110

ent disclosure and may be of any approved detail construction. However, I preferably secure to the outer side of each stirrup of frame 8, the lower end of an upright 9. 5 These uprights are provided for the purpose of supporting a cover or canopy (not shown) which serves as a protection for the workmen or masons so that they will not be injured by materials falling from above. 10 To the vertically positioned flanges of each of the angle bars 6, bracket plates 10 are secured by the bolts 11 at points adjacent the opposite ends of said angle bars. Between these brackets, the upper ends of 15 the suspension bars 12 are pivotally supported upon the bolts or rivets 13. The lower ends of said bars 12 extend between the transversely positioned angle bars 14 to which they are pivotally connected by the 20 bolts 15. The bars 14 at one of their ends extend a considerable distance laterally beyond one of the suspending bars 12, said projecting ends of the angle bars 14 throughout the length of the scaffolding being 25 connected with each other by the relatively wide longitudinally extending plate 16. Between this plate and the suspending bars 12 next adjacent to the wall of the building being erected, the boards 17 constituting the workmen's platform are 30 positioned upon the ends of the bars 14. Thus it will be seen from reference to Figure 1 that when the suspending bars 12 are perpendicularly positioned, the workmen's 35 platform 17 projects laterally beyond the edge of the material receiving platform 5. The subjacent workmen's platform may be laterally adjusted with respect to the platform 5 and the suspending bars 12 retained 40 in various angular positions with respect to said platforms by means of the link bar 18 one end of which may be adjustably connected with the suspending bar 12 which is next adjacent to the workmen's platform 17 by 45 means of the bolt 19, said bolt being engaged through any one of the series of longitudinally spaced openings 20 in the suspending bar. Intermediate of its ends the link bar 18 is twisted so that the free end thereof is 50 disposed in a plane at right angles to the end portion of the bar which is connected to the suspending bar 12. This free end of the link bar terminates in a sleeve 21 which is adapted to be disposed between the spaced 55 angle bars 6 of the put log to receive the bolt 22. Each of the angle bars is provided with longitudinally spaced bolt receiving openings 23 whereby this end of the link bar 18 may be rigidly connected with the putlog. 60 In the operation of the scaffolding as above described, it will be seen that the link bar 18 may be properly adjusted and connected with the suspending bar 12 and the putlog so as to position the workmen's 65 platform 17 in lateral spaced relation be-

neath one side of the material receiving platform 5 and rigidly retain the workmen's platform in such position that the longitudinally extending plate is disposed closely adjacent to the face of the wall being erected. 70 As shown in Figure 1 of the drawing, when the workman or mason is positioned on the platform 17, the material receiving platform is of such elevation above the workmen's platform that the workmen may have easy 75 access to the materials on the latter platform without stooping or bending from an erect or standing position. Thus the erection of the building wall will be greatly expedited. Also, it will be seen that owing to the provision of the subjacent workmen's platform 17, the materials may be loaded upon the platform 5 without in any way obstructing the movements of the workmen, thereby further 80 eliminating loss of time in the building operation. Of course it will be understood that the scaffolding may be so constructed that the platform 5 is sufficiently wide to receive wheel-barrows and permit workmen to easily pass each other, or on the other hand, 85 this platform may if desired, be made relatively narrow. 90

In many cases, the wall being erected is provided with one or more cornices or ornamental projections such as is indicated at 24, 95 and if it is necessary to raise or lower the scaffolding, the workmen's platform may be readily positioned as shown in dotted lines in Figure 1 of the drawings so as to permit said platform to safely pass by said cornice 100 or projection by merely adjusting the connection of the link bars 18 to the supporting putlog for the platform 5. After the scaffolding has been properly adjusted by means of the hoisting devices, the connection of 105 the link bars 18 with the putlogs is again changed so as to return the workmen's platform to its former position closely adjacent to the face of the building wall. 110

As shown in Figure 5, the workmen's platform may also be projected outwardly further beyond the side of the main platform 5 to extend between vertical piers or columns of the building wall by adjusting the connections between the link bars 18 and the suspending bars 12 having the openings 20 therein which adjustably receive the pivot bolts 19. Thus it will be seen that the improved scaffolding is readily adaptable for use in connection with various conditions 115 which may be encountered in the erection of buildings of various types of architecture. It will also be noted from the foregoing description that the weight of the materials on the platform 5 is disposed outwardly of the 120 workmen's platform 17. Therefore, in the event that one of the suspension cables should break, particularly in the arrangement shown in Figure 1, the sagging of the main platform would cause the subjacent 125 130

workmen's platform to be swung inwardly towards the face of the building wall through the connections between the put-logs 7 and the bars 14. The plate 16 being 5 thus forced into tight bearing engagement against the face of the wall will sustain the scaffolding against complete collapse until the necessary repairs can be made.

From the foregoing description considered in connection with the accompanying drawing, the construction, manner of operation and several advantages of my improved scaffolding will be clearly and fully understood. It will be seen that the apparatus 10 is relatively simple and that the several parts employed can be easily and quickly connected in proper operative relation. By the provision of the separate workmen's platform suspended below the main platform in the manner explained, it is obvious that the work may be greatly facilitated. The scaffold structure as herein described is such as to provide a very rigid and substantial working platform for 15 the workman upon which he may freely move without obstruction while at the same time he can have easy access to the masonry materials without frequent bending or stooping or other undue exertion. When the scaffolding is not in use, the several parts thereof may be disconnected and very compactly arranged for storage purposes.

I have herein illustrated and described an embodiment of my present improvements 20 which I have found to be entirely practical in operation. Nevertheless, it will be understood that the present disclosure is merely for the purpose of illustration and that the several novel features of my invention might be exemplified in numerous other alternative structures. Accordingly, I reserve the privilege of resorting to all such legitimate changes in the form, construction and relative arrangement of the several parts as may be fairly embodied 25 within the spirit and scope of the invention as claimed.

I claim:

1. Scaffolding, comprising a material receiving platform, a subjacent workmen's platform, adjustable suspension means sustaining the workmen's platform in suspended relation to the material receiving platform, and means connected between said platforms for positioning the workmen's platform under or adjustably to one side of said material receiving platform.

2. Scaffolding, comprising a material receiving platform, a workmen's platform, and means for suspending the workmen's

platform in subjacent relation to the material receiving platform, said means including pivotally movable suspension bars, and adjustable link bar connections between suspension bars and the material receiving platform whereby the workmen's platform may be located in various transversely adjusted positions with respect to the material receiving platform.

3. Scaffolding, comprising putlogs having hoisting devices connected therewith and a material receiving platform supported upon said putlogs, a workmen's platform, and means for suspending the workmen's platform in subjacent relation to the material receiving platform, said means including supporting bars for the workmen's platform, suspension bars pivotally connected with said supporting bars and with the putlogs, and adjustable link bar connections between certain of said suspension bars and the putlogs whereby said workmen's platform may be transversely adjusted with respect to said material receiving platform.

4. Scaffolding, comprising a material receiving platform, a workmen's platform having supporting bars extending transversely under said material platform and in subjacent relation thereto, a pair of parallel supporting links pivotally connected with each of said bars and with the receiving platform whereby said workmen's platform is adapted to swing transversely with respect to said material platform from one position with respect thereto to another, and a rigidly connected member between the material platform and a supporting link of the workmen's platform for securing said workmen's platform in various positions with respect to said material platform.

5. Scaffolding, comprising a material receiving platform, a subjacent workmen's platform projecting laterally beyond one side of the material receiving platform, means whereby said workmen's platform may be moved sidewise with respect to said material receiving platform, a rigid connecting member between the two platforms for securing the workmen's platform in adjusted position, means above the material receiving platform for suspending the two platforms as a unit at various elevations, and means mounted on the upper side of the receiving platform for raising or lowering the platforms while the workmen's platform is held in its adjusted position.

In testimony that I claim the foregoing as my invention, I have signed my name hereto.

FRANK B. JOHNSTON.
